ROLL FOR IRONERS

Joseph B. Sando, Kansas City, Mo., assignor to
Western Laundry Machinery Company, a cor-
poration of Missouri

Application July 17, 1943, Serial No. 495,180
In Canada June 11, 1943

8 Claims. (Cl. 38—65)

1

My invention relates to ironing machines, and more particularly to heated rolls for ironers, and is particularly adapted for finishing rolls for ironers. This is a continuation in part of my application Serial No. 370,039, filed December 13, 1940, on Finishing roll for flat work ironer, patented February 26, 1946, Patent No. 2,395,764.

In heated rolls for ironers, particularly wrinkle removing rolls for flat work ironers, it is desirable to provide a very highly heated surface thereon, and it is the principal purpose of my invention to provide means for heating an ironer roll in a manner such that a very high temperature can be obtained at the ironing surface. This is accomplished by providing a narrow annular passageway for the heating fluid running lengthwise of said roll closely adjacent the inner surface of the wall, the outer surface of which forms the ironing surface of the roll, and to pass a heating fluid through said narrow passage at a rapid rate to thus provide for heat exchange at a maximum temperature between the metal of the ironing surface wall and the heating fluid. The heating fluid may be either a liquid or steam. Much higher temperatures can be obtained by means of a liquid and, preferably, my invention is applied to a flat work ironer in which the heating of the stationary chests, or shoes, is accomplished by means of a liquid, such as disclosed in my Patent No. 2,324,029, patented July 13, 1943, on Heating means for ironers. However, my invention is also applicable to flat work ironers having steam heated chests. In such case it is highly desirable and necessary, however, that the wrinkle removing or other highly heated roll, be connected with a steam supply line for the ironer in such a manner that the live steam passes from the source of supply through the narrow passage in the roll at high velocity to the steam chest, or chests, of the ironer. Such ironers ordinarily have more than one chest, and in view of the fact that condensation will be taking place in these chests, there will be a constant flow of steam at high velocity through the roll on its way to one or more of the chests.

It is a particular purpose of my invention to provide a roll of the above mentioned character, which is provided with inner and outer cylindrical walls closely adjacent each other to provide a very narrow annular passage between said walls extending lengthwise of said roll which constitutes an annular slot-like passage for heating fluid running from an inlet chamber at one end of said roll to an outlet chamber at the other end thereof, through which said fluid is caused to flow at high velocity.

2

Other objects and advantages of my invention will appear as the description of the drawings proceeds. I desire to have it understood, however, that I do not intend to limit myself to the particular details shown or described, except as defined in the claims.

In the drawings:

Fig. 1 is a fragmentary vertical sectional view through a portion of an ironing machine embodying my invention, the showing being somewhat diagrammatical.

Fig. 2 is a section taken on the line 2—2 of Fig. 1, partly broken away.

Fig. 3 is a section similar to Fig. 2, of the left hand end of the roll shown in Fig. 2, on an enlarged scale.

Fig. 4 is a section taken on the line 4—4 of Fig. 3.

Fig. 5 is a section taken on the line 5—5 of Fig. 3.

Fig. 6 is a diagrammatic view of the ironing means and the means for supplying heated liquid thereto, partly broken away.

Fig. 7 is a fragmentary vertical sectional view through a portion of an ironing machine utilizing steam heated chests and including my invention, and

Fig. 8 is a fragmentary view in elevation, taken substantially on the line 8—8 of Fig. 7.

Referring in detail to the drawings, in Fig. 1 is shown an ironing machine, which has a frame, indicated generally by the numeral 10, on which is provided a receiving table 11, over which conveyor means 12, made in the form of band-like members, extends to carry the work into the machine onto the conveyor made up of a plurality of band-like members 13 that operate over a series of rolls 15, 16 and 17, said bands being driven in any desired manner, by any suitable driving means, any one of the rolls, such as the roll 15, for example, being driven from a suitable source of power and the remaining rolls rotating freely on their axes. The roll 17 is adjustable so as to vary the tension of the bands 13 and vary the pressure exerted by said bands on the ironing surface formed on the convex side of the curved bottom wall 20 of the stationary ironing member 22, supported from frame members 23 and having side walls 21, and against the surface of the roll 25. Said ironing member is heated by a liquid discharged from a liquid distributing member 24, which is described more in detail in my Patent No. 2,324,029, on Heating means for ironers, patented July 13, 1943.

A heated roll, indicated generally by the numeral 25 in Fig. 1, is provided between the roll

17 and the stationary ironing member having the convex ironing surface on the outer face of the wall 28, above referred to, said heated roll being, preferably, rotated by means of any suitable driving means, such as for example, by means of a sprocket chain extending from a driven roller, such as the roller 16, to the roll 25, suitable sprockets 26 on the roll 16, and 27 on the roll 25 being connected by means of a chain 28, and it will be noted that the sprocket 27 is substantially half the size of the sprocket 26, having substantially half the number of teeth of said sprocket 26. It will be obvious that as a result the outer surface of the roll 25 will have a lineal speed in excess of twice the lineal speed of the bands 13 where these contact the roll 25, the pressure with which said bands engage said roll being determined by the adjustment of the roll 17.

The construction of the roll 25 is shown more in detail in Figs. 2, 3, 4 and 5, comprising a central ironing portion that has an outer cylindrical wall portion 29 and an inner cylindrical wall portion 30, said wall portions being spaced apart by means of spacing members 31 so as to provide a narrow annular slot-like passage, or space, between said walls 29 and 30, the same being indicated by the numeral 32. The spacing members 31 are merely small rectangular block-like members, as will be evident from the drawings, that are welded to the outer surface of the inner cylindrical member 30 and to the inner surface of the outer cylindrical member 29 at the ends of said cylindrical members 29 and 30. Thus an annular passage 32 of a very restricted character is provided running lengthwise of the roll between the walls 29 and 30. A tubular member 33 is connected with the outer cylindrical member 29 by means of a connecting member 34, that is welded to the cylindrical member 29, and which is welded to, and fits against the shoulder 35 on the member 33. A tubular member 36 is similarly connected by means of a member 37 with the other end of the cylindrical member 29. Said tubular members 33 and 36 serve as hollow shaft portions that are mounted in the bearings 38 provided on the frame 10. The sprocket member 27 is mounted to rotate with the tubular member 33 to thus drive the roll 25.

An inlet pipe 39 is provided, which extends from a fluid heater, preferably, a heater 72 for a liquid that is of high boiling point, which is utilized for heating the roll, as well as the stationary ironing member, and a collar 40 is fixed on said inlet pipe 39, against which a rotatable collar 41 bears, said rotatable collar 41 bearing against the internal shoulder 42 provided in the tubular member 33. Said tubular member 33 is externally threaded at 43 and a packing nut 44 has internal threads engaging with the threads 43 to force a flanged collar 45, which is rotatably mounted on the member 39, into engagement with a plurality of plies of compressible packing 46. Thus a liquid tight joint is provided between the stationary pipe 39 and the rotatable tubular member 33, and said inlet pipe 39 empties into the inlet chamber 47, provided in the tubular member 33 and the connecting member 34 leading into one end of the annular passage 32. The tubular member 36 is provided with a similar means for providing a fluid tight joint between itself and the stationary outlet pipe 48, the space within the tubular member 36 and within the member 37 serving as an outlet chamber 49, which is connected with the outlet pipe 48, and into which the fluid passing lengthwise through the roll between the walls 29

and 30 discharges to be carried from the roll. It will be noted that said chambers 47 and 49 are of much greater cross sectional area than the annular slot-like passage 32.

Preferably, a liquid is utilized to heat the roll, and it will be obvious that the chamber 71 between the end walls 50 and the cylindrical wall 30 is closed off from the heating liquid, the walls 50 being welded to the wall 30, as will be obvious. 10 Thus the heating liquid circulated by the pump 73 through pipe 74 will enter through the pipe 39 into the inlet chamber 47 and then flow at a rapid rate in a thin annular stream through the narrow, thin, attenuated, or restricted, passage 32 15 lengthwise of the roll in contact with the inner surface of the wall 29, the outer surface of which serves as the convex ironing surface of the roll, and out through the outlet chamber 49 to the outlet pipe 48 back to the heating means for the heating liquid through the pump 73, or to any suitable apparatus that may be heated thereby before such return.

The roll 25 will thus be highly heated on the ironing surface thereof by the liquid, which may 25 have a temperature as high as 500 degrees Fahrenheit without boiling, and will be traveling in the direction indicated by the arrow in Fig. 1 at a rate at its surface about twice that of the conveyor bands 13.

Instead of providing the smoothing, or finishing, roll on an ironer of the type above described, the same can be applied to a conventional flat work ironer, having a stationary ironing member 51, such as shown in Fig. 7, with which the rotatable 35 padded members 52 cooperate to carry the work through the machine in engagement with said stationary shoe, or chest-like member. Said chest-like member is, preferably, provided with a plurality of chambers, or steam chests, 53, into 40 which the branch pipes 54 from the steam pipe 55 lead. The work, in a machine of this character, is fed from a table 56 by means of band-like members 57 passing over the same toward the stationary ironing member 51, and in the particular 45 machine shown, additional conveyor bands 58 are provided, operating over the rolls 59 and 60 for feeding the work to the stationary ironing member. Cooperating with said conveyor members 58 is a heated wrinkle removing finishing roll 25', 50 similar to the roll 25 in all respects, except as described below.

A pair of flexible aprons, of an endless belt-like character, 61 and 62 are provided in a machine of this character, the apron 61 carrying the work under the stationary ironing member 51 in engagement therewith from left to right after the same has passed from right to left of the ironing member on top of the ironing member, and then said aprons 61 and 62 carry the work back between the same to the other end of the machine, which is not shown. The apron 62 is driven by means of a driven roll 63 and, preferably, the roll 60 is driven from the roll 63 by means of a sprocket chain 64, while the roll 25' is driven by means of a sprocket chain 65 operating over a sprocket wheel 66, which rotates with the driven conveyor roll 52, and over a sprocket 67 mounted to rotate with the roll 25'. The rate of rotation of the rolls 52 and 63 and the size of the sprockets utilized is such that the roll 25' will rotate at substantially twice the lineal surface speed of the roll 60, and thus the lineal surface speed of the roll 25' will be substantially twice the lineal speed of the bands 58.

Referring to Fig. 8, an inlet pipe 68 for live

steam is provided, which enters the inlet chamber provided at the right hand end of the roll 25', as shown in Fig. 8, passing through the narrow passage between the inner and outer cylindrical portions 29 and 30, previously described, and through the outlet chamber into the discharge pipe 69. The discharge pipe 69 is connected with the pipe 55, as will be obvious from Fig. 7, which supplies the steam to the chests 53, and the chests 53 are provided with suitable return conduits, which may be provided with suitable traps, and so on, as is customary, between the same and the boiler, or other means for creating the steam, which is not shown, as the same is conventional.

It will be obvious that a rapid flow of steam through the narrow annular passage provided in the roll 25' adjoining the ironing surface, will be obtained due to the fact that the live steam will be drawn through the same at a rapid rate as condensation takes place in the chests 53, and that the ironing surface of the roll 25' can be heated to as high a temperature as is possible with steam, without using unduly high and unsafe pressures. Also the heating of the roll 25' will be such that it will have a high enough temperature as to instantaneously remove the wrinkles from the work as the same is brought into engagement with said roll by the conveying means 58. The roll 25' is, of course, mounted in suitable bearings on the frame 70 of the ironing machine, and the sprocket wheel 67 is, of course, fixed to the tubular member 33 in a similar manner to that described in connection with the form of the invention shown in Figs. 1 to 5, inclusive.

What I claim is:

1. In a flat work ironer, a roll, and means for heating said roll comprising means providing an annular restricted passage adjoining the ironing surface thereof, means for passing live steam through said passage lengthwise of said roll and means for accelerating the rate of flow of steam therethrough comprising a steam chest of said ironer connected with the discharge end of said passage.

2. In a laundry machine, a rotatable cylindrical member of much greater length than diameter and means for heating the same, said rotatable member comprising a pair of long imperforate tubular members coaxially arranged one within the other, the outer diameter of the inner tubular member closely approaching the inner diameter of the outer tubular member to define a long narrow slot-like smooth walled duct of uniform annular cross section and unobstructed from end to end thereof therebetween, said inner tubular member being closed at its ends, an inlet chamber at one end of said rotatable member leading endwise into one end of said duct, an outlet chamber at the other end of said rotatable member leading endwise from the other end of said duct, an inlet for heating fluid leading centrally into said inlet chamber, an outlet for heating fluid leading centrally from said outlet chamber, said inlet and outlet chambers and said heating fluid inlet and outlet being all of much greater cross sectional area than said duct to induce rapid flow of heating fluid through said duct parallel to the axis of said cylindrical member, and means for withdrawing heating fluid from said outlet.

3. In an ironing machine, an elongated tubular roll of a diameter that is a small fraction of its length having inner and outer closely adjacent but slightly spaced walls each of uniform di-

ameter throughout the length thereof defining an annular restricted smooth walled but unobstructed passage between the same, the space between said walls being minute in relation to the length of said passage, an inlet chamber at one end of said roll opening directly into one end of said passage, an outlet chamber at the other end of said roll opening directly into the other end of said passage, said chambers being of greater cross sectional area than said passage, said passage being otherwise closed and being of uniform cross section from end to end thereof, means for introducing heating fluid into said inlet chamber, an outlet connection leading from said outlet chamber, and means for creating a positive flow of fluid lengthwise of said roll from said inlet chamber to said outlet chamber.

4. In an ironing machine, an axially elongated rotatable member, and means for heating the same, comprising an inner closed ended elongated pipe-like tube and an outer open ended elongated pipe-like tube, the inner wall of said outer tube and the outer wall of said inner tube being closely spaced throughout their length to define an attenuated smooth walled unobstructed annular duct extending between said walls lengthwise of said rotatable member and being of the same cross section from end to end thereof, and means for passing a heating fluid into said member at one end thereof directly into said passage through said passage at high velocity and out of said member at the other end thereof directly from said passage.

5. In an ironing machine, an elongated tubular roll of a diameter that is a small fraction of its length having a cylindrical wall providing an ironing surface on the outer side thereof, and means for heating said ironing surface to a high temperature, comprising an elongated tubular member of uniform external diameter slightly smaller in diameter than the bore of said cylindrical wall co-axially arranged within the same to provide a long narrow slit-like unobstructed heating fluid conduit of uniform cross sectional area co-extensive with said cylindrical wall and extending lengthwise of said roll closely adjacent said ironing surface, and means for creating a rapid uniform flow of heating fluid lengthwise of said roll through said conduit from one end to the other end of said cylindrical wall.

6. In an ironing machine, an elongated tubular roll of a diameter that is a small fraction of its length comprising an outer elongated tube providing an ironing surface on the outer side thereof, and means for heating said ironing surface to a high temperature, comprising an inner elongated tube of uniform external diameter and of slightly smaller diameter than and co-axially arranged within said outer tube, thin spacing means between said tubes at the ends of the latter so as to provide a long narrow slit-like unobstructed heating fluid duct of uniform cross sectional area co-extensive with said ironing surface and extending lengthwise of said roll so as to be closely adjacent said ironing surface and means for creating a rapid uniform flow of heating fluid lengthwise of said duct through said duct from one end to the other end of said tubular roll, comprising an unobstructed inlet chamber at one end of said duct open thereto to substantially the full cross sectional area of said duct, an unobstructed outlet chamber at the other end of said duct open thereto to substantially the full cross sectional area of said duct, said chambers being 70 75 of greater cross sectional area than said duct,

means for supplying heating fluid to said inlet chamber and means for discharging said fluid from said outlet chamber.

7. In a laundry machine, a rotatable cylindrical roll having a diameter that is a small fraction of its length, said roll comprising an inner pipe-like imperforate tubular member of uniform external diameter closed at its ends and an outer pipe-like imperforate tubular member of uniform inner and outer diameter, thin spacing means between said inner and outer members to mount said members co-axially in close adjacency to define an unobstructed long narrow slot-like duct of uniform cross section between said members extending lengthwise of said roll from end to end of said inner pipe-like member, and means for heating said roll comprising means for rapidly passing heating fluid lengthwise of said roll through said duct.

8. In a laundry machine, a rotatable cylindrical roll having a diameter that is a small fraction of its length, said roll comprising an inner pipe-like imperforate tubular member of uniform external diameter closed at its ends and an outer pipe-like imperforate tubular member of uniform inner and outer diameter, thin spacing means between said inner and outer members to mount said members co-axially in close adjacency to define an unobstructed long narrow slot-like duct of uniform cross section between said members extending lengthwise of said roll from end to end of said inner pipe-like member, and means for heating said roll comprising means for rapidly passing heating fluid lengthwise of said roll

through said duct, comprising an inlet chamber of larger cross sectional area than said duct at one end of said roll opening endwise into said duct, an inlet connection of larger cross sectional area than said duct leading into said inlet chamber, an outlet chamber of larger cross sectional area than said duct at the other end of said roll into which said duct opens endwise, an outlet connection of larger cross sectional area than said duct leading from said outlet chamber and means for rapidly withdrawing fluid from said outlet connection.
